Henry O'Doherty Baltimore Md

Letter Patent

X 9494

The substance referred to in these Letters Patent are making part of the same Patent as a Description in the words of the late James Hargrave, Inventor, of his Improvement in the Construction of Piano Fortes.

In all the above these present shall come. We it known that Henry O'Doherty of the City of Baltimore in the State of Maryland has invented and we are Improvement in the Construction of Piano Fortes and that the following is a full and exact Description of the Construction of the said Improvement as intended by me in the necessary Novelty of Constructing Piano Fortes the turning pins & turning while the Tension of the strings is increased or diminished as may be required to put the instrument in tune are inserted into a solid block of wood, & stood in the proper places, so lightly that the friction or adhesion of the metal of the pins give to the wooden turning block, as it is technically termed, a sort of pivot to prevent the turning pins from being turned by the tension of the strings which is kept increased by it. The wood however being softer than the turning pins and casting in itself it often happens that the pins will without being turned down by the tension of the strings, get into a perpendicular position after the pins have turned wholly the tension of the strings being diminished the instrument becomes as it is called at a time. This is the more liable to be the case the higher the key or pitch to which the piano is tuned. Owing to the volatility of the wood block may under this circumstance or giving way of the turning pins different in different parts of the same piano, & this is its voluntary. Now the Construction may however remain perfectly in their proper position and the instrument nevertheless become out of tune by the whole turning block being yielding to the tension of the strings. It is for the purpose of obviating these difficulties so far as it can be done by keeping the turning pins, pins and the turning block in its proper position that my improvement is made, and I effect this object in the following manner. I prepare a wooden plate of the height of the turning block and of a sufficient width to rest upon

secured fast to the tuning block the tuning of the strings, with circular holes
exactly corresponding with the holes for the tuning pins in the tuning block.
The holes in the metallic plate are just large enough to permit the tuning
pins to move around smoothly, with the least play between the pins and
the metallic plate. The tuning pins are prevented from turning around
(by the tension of the strings) in this. But as in any other by the friction
against the wood of the tuning block and by means of the metallic
plate they are prevented from coming out of their perpendicular position
and the tuning block is made firm enough to resist the accumulated
tension of all the strings, which rest on the metallic plate just described.
Enunciates the improvement, which I have invented in the piano, which
I have made with a view of testing the utility of my invention the thickness
of the metallic plate has been about three eighths of an inch, & had I
been forced to do so I shall though it may be made in different different
& dimensions in this respect and still produce the same effect. It may
also be made of brass or iron or other metal, I have hitherto used iron. The
metallic plate here described is secured fast to the tuning block and is secured
fast by a screw or other sufficient fastening to the metallic plate which is
above the sounding board and upon which the strings are hung or fastened
all firmly. In the accompanying drawing but one construction of
piano is shown. My improvement is equally applicable to any other
that I claim as new and as my own invention in the above and for the
use of which I ask an exclusive privilege is the metallic plate fastened
to the tuning block, with holes for the tuning pins to pass through, giving
additional security and permanency to such pins and giving increased
firmness to the tuning block, thereby aiding to keep the instrument in tune
longer.
